UNITED STATES PATENT OFFICE

131,924

DESIGN FOR A CONDIMENT SHAKER OR THE LIKE

Jack G. Williams, Detroit, Mich., assignor to Brooke, Smith, French & Dorrance, Inc., Detroit, Mich., a corporation of Michigan

Application April 14, 1941, Serial No. 100,367

Term of patent 7 years

To all whom it may concern:

Be it known that I, Jack G. Williams, a citizen of the United States, residing at Detroit, in the county of Wayne and State of Michigan, have invented a new, original, and ornamental Design for a Condiment Shaker or the like, of which the following is a specification, reference being had to the accompanying drawing, forming part thereof,

In the drawing:

Fig. 1 is a perspective view of a condiment shaker or the like, showing my new design; and Fig. 2 is a front elevational view of the same.

I claim:

The ornamental design for a condiment shaker or the like, as shown.

JACK G. WILLIAMS.
